(57) **ABSTRACT**

A new cultivar of *Buddleja* plant named 'Botex 001' that is characterized by its very compact, dense, and upright-rounded plant habit, its flowers that are intense purple in color, its very floriferous blooming habit, and its flowers that have a pleasant fragrance.

2 Drawing Sheets

1

Botanical classification: *Buddleja davidii*.
Variety denomination: 'Botex 001'.

**CROSS-REFERENCE TO RELATED
APPLICATIONS**

This application claims priority to European Community Plant Variety Office (CPVO) Plant Breeder's Rights Application No. 2020/3377 filed on Jan. 13, 2021, under 35 U.S.C. 119(f), the entire contents of which is incorporated by reference herein. This application is also co-pending with a U.S. Plant Patent Application filed for a plant derived from the same breeding program from the same parentage that is entitled *Buddleja* Plant Named 'Botex 002' (U.S. Plant patent application Ser. No. 17/556,977).

BACKGROUND OF THE INVENTION

The present invention relates to a new and distinct cultivar of *Buddleja davidii* will be referred to hereafter by its cultivar name, 'Botex 001'. 'Botex 001' is a new shrub grown for use as an ornamental landscape plant.

The new cultivar of *Buddleja* is a selection from an ongoing breeding program conducted by the Inventor in Kaatsheuvel, The Netherlands with the objective of creating new cultivars of *Buddleja* with very neat and compact plant habits combined with unique flower colors and floriferous blooming habits.

The Inventor made a cross in summer of 2018 between an unnamed and unpatented proprietary plants in the Inventor's breeding program; reference no. 11010 as the female parent and reference no. 263 as the male parent. The Inventor

2

selected 'Botex 001' in summer of 2019 as a single unique plant amongst the seedlings that resulted from the above cross.

Asexual propagation of the new cultivar was first accomplished by the Inventor using stem cuttings in Kaatsheuvel, The Netherlands in August of 2019. Asexual propagation by stem cuttings has determined that the characteristics of the new cultivar are stable and are reproduced true to type in successive generations.

SUMMARY OF THE INVENTION

The following traits have been repeatedly observed and represent the characteristics of the new cultivar. These attributes in combination distinguish 'Botex 001' as a unique cultivar of *Buddleja*.

1. 'Botex 001' exhibits a very compact, dense, and upright-rounded plant habit.
2. 'Botex 001' exhibits flowers that are intense purple in color.
3. 'Botex 001' exhibits a very floriferous blooming habit.
4. 'Botex 001' exhibits flowers that have a pleasant fragrance.

The female parent of 'Botex 001' differs from 'Botex 001' in having inflorescences that are shorter in length with flowers that are lighter purple in color and in having a less upright and more spreading plant habit. The male parent of 'Botex 001' differs from 'Botex 001' in having inflorescences that are smaller in size and less dense with flower centers that are purple in color and in having a less upright and more spreading plant habit. 'Botex 001' can also be compared to the *Buddleja* cultivars 'Nanho Purple' (not patented) and 'BotEx 002'. 'Nanho Purple' differs from 'Botex 001' in having a taller plant height and spreading

plant habit with arching branches. 'Botex 002' differs from 'Botex 001' in having a more spreading plant habit and flowers that are lighter and more lilac in color.

STATEMENT REGARDING PRIOR
DISCLOSURES BY THE INVENTOR

The Applicant asserts that no publications or advertisements relating to sales, offers for sale, or public distribution occurred more than one year prior to the effective filing date of this application. Any information about the claimed plant would have been obtained from a direct or indirect disclosure from the Inventor. The Applicant claims a prior art exemption under 35 U.S.C. 102(b)(1) for disclosure and/or sales prior to the filing date but less than one year prior to the effective filing date. Disclosures include but may not be limited to website listings by Podoslonami, Groen Vandaag, Plantago, Greenport, Gabot, Bloemenkrant, Floricade, Plamntipp, Hortipoint, CG Concept, Stad+Groen, Floranews, Tuinzaken, Handel & Techniek, Van Son & Koot BV, KVBC, Perishablenews, Hortweek, Buddlejagarden, Boom-in-Business, Greenity, and Obst & Garden.

BRIEF DESCRIPTION OF THE DRAWINGS

The accompanying color photographs illustrate the overall appearance and distinct characteristics of the new *Buddleja*.

The photograph in FIG. 1 was taken of a plant about 3 years in age as grown outdoors in a trial garden in Kaatsheuvel, The Netherlands. The photograph in FIG. 1 provides a side view of the overall plant habit of 'Botex 001' in bloom.

The photographs in FIG. 2 and FIG. 3 were taken of a 1-year-old plant as grown in a 19-cm container in a greenhouse in Kaatsheuvel, The Netherlands.

The photograph in FIG. 2 provides a close-up view of an inflorescence of 'Botex 001'.

The photograph in FIG. 3 provides a close-up view of a leaf of 'Botex 001'.

The colors in the photographs are as close as possible with the photographic and printing technology utilized and the color values cited in the Detailed Botanical Description accurately describe the colors of the new *Buddleja*.

DETAILED BOTANICAL DESCRIPTION

The following is a detailed description of one-year-old plants as grown in a greenhouse in 19-cm containers in Kaatsheuvel, The Netherlands. The phenotype of the new cultivar may vary with variations in environmental, climatic, and cultural conditions, as it has not been tested under all possible environmental conditions. The color determination is in accordance with The 2015 Colour Chart of The Royal Horticultural Society, London, England, except where general color terms of ordinary dictionary significance are used. General description:

Blooming period.—July to October in The Netherlands.

Plant type.—Deciduous perennial shrub.

Plant habit.—Compact, upright-rounded, dense.

Plant size.—An average of 35 cm in height and 43 cm in width as a one-year-old plant in a container and an average of 80 cm in height and 80 to 90 cm in height when grown in the landscape.

Cold hardiness.—At least in U.S.D.A. Zone 5.

Diseases and pests.—No susceptibility and resistance to diseases or pests has been observed.

Propagation.—Stem cuttings.

Root description.—Fibrous.

Root development.—An average of 8 weeks to initiate roots and eight weeks to fully root as a young plant in a P9 container.

Growth rate.—Vigorous.

Branch description:

Branch shape.—Quadrangular.

Branch color.—Young stems; 145B, mature stems; 199A.

Branch strength.—Strong.

Branch size.—An average of 26 cm in length and 5 mm in diameter.

Branch surface.—Pubescent.

Branch internode length.—Average of 2 cm.

Branching.—1 main branch, 4 lateral branches.

Foliage description:

Leaf shape.—Narrowly elliptical to elliptical.

Leaf division.—Simple.

Leaf base.—Attenuate.

Leaf apex.—Acute.

Leaf fragrance.—None.

Leaf venation.—Pinnate, color; upper surface 144A, lower surface 191D with main vein 145B.

Leaf margins.—Serrate.

Leaf arrangement.—Opposite.

Leaf attachment.—Petiolate.

Leaf surface.—Both sides are smooth and matte, lower surface pubescent.

Leaf size.—An average of 11 cm in length and 3.1 cm in width.

Leaf quantity.—An average of 10 per stem.

Leaf color.—Young upper surface; 137C, base 145C, young lower surface; 191A, mature upper surface; 137A, mature lower surface; 191D.

Petioles.—An average of 5 mm in length and 2 mm in diameter, medium to high strength, both surfaces 145B in color, upper surface smooth and glabrous, lower surface slightly pubescent.

Inflorescence description:

Inflorescence type.—Compound terminal and axial panicles.

Inflorescence size.—An average of 5.3 cm in height, 3.8 cm in width.

Flower fragrance.—Sweet, pleasant and medium strength.

Lastingness of flowers.—An average of 5 days, persistent, inflorescence is semi-indeterminate.

Flower buds.—Oblong, average of 6 mm in length and 1 mm in diameter, 83A in color.

Flower aspect.—Upright.

Flower quantity.—An average of 150 flowers per inflorescence.

Flower type.—Single, salverform.

Flower surface.—All surfaces glabrous and smooth.

Flower size.—An average of 7 mm in height, 1.2 cm in depth, flower throat; 1 mm in diameter, flower tube; 3 mm in length, 1 mm in diameter.

Peduncles.—An average of 2 cm in length and 2.5 mm in diameter, held erect, 145A in color, strong, glossy and pubescent surface.

US PP34,515 P3

5

Pedicels.—An average of 2 mm in length and 1 mm in diameter, held at an average angle of 45°, 145B in color, strong, surface is glossy and pubescent.

Calyx.—Campanulate in shape, an average of 2 mm in depth and 1 mm in diameter.

Sepals.—4, 1 whorl, rotate arrangement, fused into a campanulate shape, 2 mm in length, 1.5 mm in width, lanceolate in shape, acute apex, fused base, entire margin, both surface are matte and slightly pubescent, color; when opening and fully open upper and lower surface 145A.

Petals.—Average of 4, rotate, fused into salverform, 1 whorl, roughly spatulate in shape, slightly undulate margin, rounded apex, an average of 3 mm in length and width, upper and lower surface is glabrous, velvety and matte, color; upper and lower surface

5

10

15

6

when opening and fully open 90B, center 23A, flower throat 77A, flower tube 21B, base 77A.

Reproductive organs:

Gynoecium.—1 pistil, 3 mm in length, style; an average of 2 mm in length, 145D in color, stigma; elongated, 1 mm in length and 145B in color, ovary is 145D in color.

Androcoecium.—Stamens; 4, filament; 4 mm in length and 20B in color, anther; ovate in shape, 1 mm in length, 11D in color, pollen; low in quantity, 11D in color.

Fruit and seed.—No seeds or fruit observed to date.

It is claimed:

1. A new and distinct cultivar of *Buddleja* plant named 'Botex 001' as herein illustrated and described.
